(57) **CLAIM**

The ornamental design for a tire tread for pneumatic tire, as shown and described.

DESCRIPTION

FIG. 1 is a front elevational view of a tire tread for pneumatic tire showing our new design, it being understood that the tire pattern repeats circumferentially throughout the outer circumference.

FIG. 2 is a perspective view of one side of the tire tread as shown in FIG. 1, wherein the other side is a mirror image.

FIG. 3 is an enlarged fragmentary front view of the tire tread; and,

FIG. 4 is a side elevational view of one side of the tire tread shown in FIG. 1, it being understood that the other side is a mirror image of FIG. 3.

In the drawings, the broken line environmental showing of a tire sidewall and inner bead and the broken line peripheral boundary between the tire shoulder and sidewall form no part of the claimed design.
